(57) **CLAIM**

The ornamental design for a motorcycle wind deflector, as shown and described.

DESCRIPTION

FIG. 1 is front view of a motorcycle wind deflector installed on a motorcycle and showing my new design;

FIG. 2 is an enlarged rear perspective view of the motorcycle wind deflector shown in FIG. 1;

FIG. 3 is a bottom view of FIG. 2;

FIG. 4 is a left side elevational view of FIG. 2;

FIG. 5 is a front view of FIG. 2 thereof;

FIG. 6 is a top plan view of FIG. 3;

FIG. 7 is a right side elevational view of FIG. 4; and,

FIG. 8 is a rear view of FIG. 5.

The broken lines shown are for illustrative purposes only and form no part of the claimed design.
